AIR CONDITIONING UNIT

Allen C. Staley, Birmingham, Mich., assignor to
 Chrysler Corporation, Highland Park, Mich.,
 a corporation of Delaware

Application January 27, 1936, Serial No. 61,022

4 Claims. (Cl. 257—138)

This invention relates to an improved air conditioning device.

More particularly the invention pertains to improvements in unit type air conditioning apparatus of the character suitable for installation directly in the enclosure in which air is being conditioned.

One of the main objects of the invention is to provide a unitary, compact and inexpensive device of this character which is regular in shape and accommodatable in space of limited size.

Other objects of the invention are to provide improved means in air conditioning units of this kind for selectively varying the amount of conditioned and unconditioned air discharged therefrom; to provide a heat transfer member for conditioning air passing through the unit and an adjacent by-pass passage for the unconditioned portion of the discharge from the unit; to provide means for selectively supplying air to said passage and heat transfer member which has an air discharge outlet so disposed as to direct the main portion of its discharge toward the inlet end of the passage; to provide an adjustable closure for the inlet end of the by-pass passage which is inclined so as to direct all, or a portion of the air discharged from said means to the heat transfer member; to provide for the flow of that portion of air discharge which passes directly to the transfer member in a sweeping course of unabrupt directional change so as to avoid excessive obstruction of air flow and to accommodate the passage of a comparatively large quantity of air through the transfer member; to provide an improved heat transfer member, by-pass passage and blower discharge arrangement of this character by which comparatively large quantities of air may be discharged from the unit when only a relatively small opening is present at the inlet end of the by-pass passage; and to provide a closure for the by-pass passage which is conveniently adjustable by relatively simple and inexpensive apparatus that is operable from the exterior of the unit.

An illustrative embodiment of the invention is shown in the accompanying drawings, in which:

Fig. 1 is a transverse, vertical, sectional view of an air conditioning unit embodying the invention.

Fig. 2 is a longitudinal, vertical, sectional view taken on the line 2—2 of Fig. 1.

Fig. 3 is a fragmentary, transverse, sectional view taken on the line 3—3 of Fig. 2.

Fig. 4 is an enlarged, fragmentary, horizontal, sectional view taken on the line 4—4 of Fig. 1.

In the form of the invention illustrated in the drawings, my improved air conditioning unit includes a rectangular base portion 10, preferably comprising sheet metal, provided with side walls 11 in which longitudinally extending inlet openings 12 are formed. The upper marginal portions of the walls of the base structure 10 are inwardly offset as indicated at 13, to provide for the reception of a casing 15 which encloses all of the air conditioning unit above the upper end portion of the base 10. Mounted on the upper extremity of the base structure 10 is a substantially horizontal top wall or partition 16 having upwardly extending marginal flanges 17 which provide a relatively flat pan-like receptacle. Formed in the partition 16 are longitudinally spaced openings 18 which are located adjacent the left side of the unit, as shown in Fig. 1.

A pair of blowers 18 are disposed within the base structure 10 and provided with discharge outlets 19 each of which communicates with one of the openings in the partition 16. The blowers 18 are preferably supported in suspended relation from the partition 16 and the upper end portions of their discharge outlets 19 are provided with flanges which are riveted, or otherwise suitably secured, to the lower side of the partition 16 as illustrated at 20 in Fig. 1.

The blowers are driven by a common motor 21 having a shaft 22 provided with opposite end sections, one of which is drivingly connected with the rotor of each blower respectively. The motor 21 is also preferably supported in suspended relation from the partition 16, preferably by a bracket 23, as illustrated in Fig. 2.

Rigidly mounted on the upper wall 16 of the base structure 10 is a casing, generally designated by the numeral 24, into which both the discharge outlets 19 of the two blowers deliver air. The casing 24 has an open lower extremity and opposite vertical side walls 25 and 26 which are provided along their lower marginal portions with inwardly extending flanges 27. The flanges 27 of the walls of the casing 24 are secured by bolts 28 to the top wall of the base structure 10 or fixed thereto in any suitable manner. The right vertical side wall of the casing 24 extends only part way to the upper elevation or top wall of the latter with which it is connected by an inclined wall section 29.

The inclined wall section 29 of the casing 24 is provided with a longitudinally extending opening 30 having outwardly offset marginal portions of the wall section 29 bounding its perimeter. Seated in the recess provided by the outwardly

offset marginal portions 31 is a gasket 32 comprising compressible material such as felt or rubber. A closure 33 for the opening 30 is provided in the interior of the casing 24 and 5 pivotally attached to the inclined wall portion 29 thereof along its upper longitudinal edge, as illustrated at 34. The closure 33 has a bracket 36 on its upper side to which a chain 37 is attached. The chain extends upwardly, passes 10 through a slot in the left wall of the outer casing 15 of the unit and has an external portion releasably engageable in a bayonet type slot 38 formed in a bracket 39 mounted on the upper end portion of the left side wall of the outer casing. 15 The closure 33 is normally urged inwardly toward an open position by a spring 40 which bears between the bracket 41 on the closure and the inclined wall section 29 of the casing 24. It may, however, be held in a completely closed 20 position or in any selected partially open position by the chain 37 which may be manually adjusted by engaging selected links thereof in the bayonet slot 38.

The discharge outlets 19 of the blower are 25 located directly below the opening 30 in the inclined wall section 29 and they therefore direct the discharges of the blower toward this opening. Mounted in the lower portion of the casing 24 in slightly overlapping relation with the paths 30 of the air discharged from the blowers 18 in a tank 41 for receiving condensate and liquid derived from a heat transfer member and spray nozzles, hereinafter described.

Mounted on the upper horizontal portion 42 of 35 the extremity of the casing 24 is a heat transfer member 43 comprising a series of turns of a coil 44 and parallel vertically disposed fin plates 45. The coil 44 of the heat transfer member 43 may be supplied with either a heating or cooling medium from an external source remote from the cooling unit, or cooling medium may be supplied thereto from suitable refrigerating means (not shown) built in or adjacent the unit. The heat transfer unit 43 extends from within close 40 proximity to the right side of the unit, as viewed in Fig. 1, to a location adjacent the right extremity of the inclined wall section 29 of the casing 24, thus providing a by-pass passage 46 between the heat transfer member and the left 45 side wall of the unit, as illustrated in Fig. 1. The opening 30 in the inclined wall section 29 serves as the inlet to the by-pass passage and an outlet therefrom is provided in the top wall of the outer casing 15 by a grill 47 which extends over the outlet end of the by-pass passage 46 and over 50 the discharge end of the heat transfer member 43.

The opposite ends of the heat transfer member 43 are closed by vertical end walls 48 having outwardly extending flanges 49. Mounted on the 55 flange 48 of the left end wall 48 shown in Fig. 2, is a tank 50 having an inlet pipe 51 communicating therewith and leading from an external source of water supply. The tank 50 has an outlet communicating with one or more horizontally 60 extending pipes 52 disposed over the discharge end of the heat transfer member 43. The pipes 52 are provided with discharge outlets or nozzle opening 53 by which water, preferably in the form of a relatively fine spray, may be sprayed in a direction opposite to the flow of air through the heat transfer member. The water spray is preferably used for humidifying the air when the unit is employed for heating purposes. It may, if desired, also be used while a cooling medium 65 is being circulated through the coil 44. Any

excess water derived from the spray system or condensed by the coils 44 is collected in the tank 41 from which it drains into the drip pan 17 and from the latter through the outlet pipe 54 which is preferably connected to the drain pipe of the building in which the unit is installed. The drip pan 17 extends beyond the side walls 25 and 26 of the casing for collecting moisture condensed therein.

Air entering the lower portion of the unit is 10 preferably cleaned by passing through filters 55 before entering the blowers 18. The filters are vertically disposed and detachably mounted on the sides of the base structure 10 of the unit by bolts 56. The filters are wholly concealed 15 from view within the interior of the sheet metal base structure 10 and they are preferably located in registration with the inlet openings 12 thereof. The outer casing 15 may be provided with corresponding inlet openings registering with the 20 inlet openings 12 or if desired the outer casing may be provided with short corner legs by which the sheet metal wall structure thereof is held in spaced relation with the floor so as to permit the flow of air thereunder.

In operation, while the blowers 18 are driven, each blower discharges a current of air directly toward the inclined wall section 29. When the closure 33 is in its closed position, as illustrated in the drawings all of the air discharged by the 30 blower 18 is deflected rightwardly, as viewed in Fig. 1. The rounded contour of the moisture collecting tank 41 guides the flow of air in gently sweeping course somewhat toward the upper end portion of the inclined wall section 29, and the 35 pressure of the air built up on the section 29 and closure provides a lateral sweeping curvilinear path for air flow to the inlet end of the heat transfer member. When the closure 33 is open, some of the air discharged by the blowers is admitted directly to the inlet end of the by-pass passage 46. Inasmuch as the inlet end of this passage is in direct registration with the outlet of the blower, only a slight amount of opening of the closure 33 is required to by-pass a substantial 40 quantity of air. The remaining portion of the air discharged by the blowers 18 is directed rightwardly, as viewed in Fig. 1, in the above manner. The rightwardly deflected portion of the air current then passes upwardly through the heat 45 transfer member 43 and is ultimately discharged through the grill provided in the upper wall of the external casing 15. In this manner, circulation of a substantially constant quantity of air within the room may be maintained while varying the temperature and humidity conditions in the air of the room by changing the portions of the circulated air which are subjected to treatment in the heat transfer member and by-passed 50 through the passage 46 respectively.

Although but one specific embodiment of the invention is herein shown and described, it will be understood that various changes may be made in the size, shape and arrangement of parts, without departing from the spirit of my invention.

What I claim is:

1. An air conditioning unit including a casing having spaced air inlet and outlet openings, a heat transfer member in said casing adjacent said outlet opening, a by-pass passage laterally 70 adjacent said member for conducting air around said member as it flows from one of said openings to the other, a blower discharge chamber aligned vertically with said member and said passage having a tank therein aligned vertically 75

with only said member, and a blower having an outlet opening into said discharge chamber and spaced from the inlet ends of said member and passage and so disposed as to discharge air in a 5 course laterally adjacent said tank and directly toward the inlet of said by-pass passage.

2. An air conditioning unit including a casing having spaced air inlet and outlet openings, a heat transfer member in said casing between said 10 openings, a by-pass passage between said inlet and outlet openings and laterally adjacent said member for conducting air around said member as it flows from one of said openings to the other, a blower discharge chamber below said 15 member and passage, a tank in said chamber aligned vertically with said member and misaligned with said passage, a blower having an outlet spaced from the inlet ends of said member and passage and so disposed as to discharge air 20 into said chamber directly toward the inlet of said by-pass passage, and a variable closure for the inlet end of said by-pass passage slanting toward the inlet end of said heat transfer member for controlling the amount of blower 25 charged air admitted to said passage and directing the remainder thereof toward the inlet end of said heat transfer member.

3. An air conditioning unit including a casing having an air outlet opening in its upper wall, 30 a heat transfer member in said casing located at the upper end thereof and having an outlet end registering with less than the entire area of said outlet opening and having an inlet end, a by-pass passage in said casing laterally adjacent 35 said heat transfer member having an outlet end registering with the remaining portion of the outlet opening of said casing and having an inlet

end laterally adjacent the inlet end of said member, a partition in said casing inclined toward the inlet end of said member for directing air to the latter and having an opening therein for admitting air to said by-pass passage, a blower discharge chamber below said passage and below and communicating with said member and the opening of said partition, a tank in said chamber vertically aligned with said member and laterally spaced from the opening in said partition, a variable closure for said inlet opening of said partition, said casing having an inlet spaced laterally from the inlet of said member and registering with the inlet end of said by-pass passage, and a blower having a discharge 15 opening communicating with the inlet of said casing and adapted to discharge air into said chamber and directly upon said partition.

4. An air conditioning unit including a casing having an air outlet opening in its upper wall, 20 a cooling member in the upper end portion of said casing having an outlet registering with a portion less than the entire area of said outlet opening and providing a by-pass passage between one of its sides and one side wall of said casing, 25 a blower having an air discharge outlet registering substantially vertically with said passage, a tank in said casing below said cooling member for the reception of condensed moisture and having an upright wall portion located adjacent the outlet of said blower for cooperating with said wall of said casing in directing the discharge of said blower to said passage, and variable means 30 for deflecting all or selected portions of said blower discharge to said cooling member. 35

ALLEN C. STALEY.
